UNITED STATES PATENT OFFICE.

ALBERT AICHELE, OF BADEN, SWITZERLAND, ASSIGNOR TO AETIENGESELLSCHAFT
BROWN BOVERI & CIE., OF BADEN, SWITZERLAND.

DEVICE ON TRANSFORMERS FOR PREVENTING THE DECOMPOSITION OF OIL BY THE
OXYGEN CONTAINED IN AIR.

1,088,197.

Specification of Letters Patent. Patented Feb. 24, 1914.

Application filed December 15, 1911. Serial No. 665,896.

To all whom it may concern:

Be it known that I, ALBERT AICHELE, a citizen of the Swiss Republic, and residing at Baden, Switzerland, have invented a certain new and useful Device on Transformers for Preventing the Decomposition of Oil by the Oxygen Contained in Air, of which the following is a specification.

This invention relates to the protection of oil in transformers from oxidization due to contact with normal or heated air. In transformers in which oil is employed difficulties arise due to this in practice which ordinarily necessitate hermetically sealing the transformer box to prevent oxidation of the oil.

The object of the present invention is to provide an improved method and means for this purpose which does not require the transformer box to be sealed hermetically.

The invention consists in the provision between the transformer oil or the main bulk thereof and the air of a diaphragm or the like with or without a further quantity of oil, means also being provided whereby expansion of the oil on heating is permitted to take place without causing injury or rise of pressure.

Referring to the accompanying diagrammatic drawings, Figure 1 shows one manner of applying the invention to an air cooled transformer, and Fig. 2 to a water cooled transformer.

In the form of the invention illustrated in Fig. 1, the transformer coils indicated by *b* are placed inside a containing case *a* through the cover *c* of which are passed the bobbin leads. The cover *c* does not form a hermetic closure with the case *a*, holes *e* being provided through which air can pass inside the case. The case *a* is substantially filled with oil but sufficient room is left to permit the oil to expand on heating. In the space *f* above the surface of the oil there is provided material such as cork, a non-conductor of heat and electricity and lighter than oil. With a transformer of this kind air can be freely passed through the ventilating holes *e* without seriously affecting the hot oil and the expansion of this oil on

heating can readily move the non-conducting mass *g*, which may be formed of a single plate or slab or a number of such plates.

In the form of the invention shown in Fig. 2 a modified system is applied to a water cooled transformer. In this case a diaphragm *j* which may be of wood is arranged at some little depth below the surface of the oil and perforated to permit expansion of the oil on heating. Water cooling coils *h* are also provided and these can be arranged as shown both in the main bulk of the oil below the diaphragm and in the part above. In operation this small part of the oil above the diaphragm constitutes a seal and hence no oxidation can take place of the oil below the diaphragm. Further any condensed water that may occur at the top of the case cannot travel down, because of the diaphragm, to the transformer coils.

In both forms of the invention the top surfaces of the insulators *g* and *j* are substantially cold and hence there is no tendency for oxidation of the chief part of the oil.

It will be understood that the modifications illustrated are given by way of example only.

Having now described my invention what I claim as new and desire to secure by Letters Patent is:

1. The combination with a transformer casing provided with apertures, a body of oil contained therein and electrical windings below the surface of said oil, of a diaphragm of insulating material disposed horizontally and in proximity with the upper level of said body of oil, in such manner as to protect the oil from oxidation by the atmosphere, substantially as described.

2. In combination, a transformer casing provided with apertures, a body of oil contained therein, electrical windings submerged in said oil, a horizontally disposed heat insulating diaphragm protecting the main bulk of the oil from the oxidizing action of the atmosphere, substantially as described.

3. In combination a transformer casing provided with apertures, a body of oil con-

tained therein, electrical windings below the surface of said oil, a horizontally disposed diaphragm of heat insulating material, supported slightly below and in proximity with the upper surface of the oil, substantially as described.

In testimony whereof I have signed my

name to this specification in the presence of two subscribing witnesses.

ALBERT AICHELE.

Witnesses:

HARRY A. McBRIDE,
AUGUST RUEGG.
